Primary Examiner — John Windmuller*Assistant Examiner* — Luqman McNeil(74) *Attorney, Agent, or Firm* — Hanrahan Law Firm, P.A.; Benjamin M. Hanrahan(57) **CLAIM**

The ornamental design for backward pants, as shown and described.

DESCRIPTION

FIG. 1 is a front view illustrating my design for backward pants.

FIG. 2 is a rear view thereof, with two slits disposed in an open position, thereby at least partially exposing an interior portion of the backward pants.

FIG. 3 is another rear view thereof, with the two slits disposed in a closed position.

FIG. 4 is a left side view thereof, with at least one slit disposed in an open position.

FIG. 5 is another left side view thereof, with the at least one slit disposed in a closed position.

FIG. 6 is a right side view thereof, with at least one slit disposed in an open position.

FIG. 7 is another right side view thereof, with the at least one slit disposed in a closed position.

FIG. 8 is a front perspective view thereof.

FIG. 9 is a rear perspective view thereof, with the two slits disposed in an open position; and,

FIG. 10 is another rear perspective view thereof, with the two slits disposed in a closed position.

The broken lines are included for the purpose of illustrating portions of the backward pants that form no part of the claimed design.
